US0D1106148S

(12) **United States Design Patent** (10) **Patent No.:** **US D1,106,148 S**
(45) **Date of Patent:** **** Dec. 16, 2025**

(54) **ELECTRONIC DEVICE**

(71) Applicant: **Elo Touch Solutions, Inc.**, Knoxville, TN (US)

(72) Inventor: **Jeffrey T. Haller**, Redwood City, CA (US)

(73) Assignee: **Elo Touch Solutions, Inc.**, Knoxville, TN (US)

(**) Term: **15 Years**

(21) Appl. No.: **29/926,419**

(22) Filed: **Jan. 30, 2024**

Related U.S. Application Data

(63) Continuation of application No. 29/762,441, filed on Dec. 16, 2020, now Pat. No. Des. 1,020,677.

(57) **CLAIM**

The ornamental design for an electronic device as shown and described.

DESCRIPTION

FIG. 1 is a top front perspective view of an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the electronic device that form no part of the claimed design.

1 Claim, 6 Drawing Sheets
